[57] ABSTRACT

The apparatus includes a mandrel, about which blank sheets are successively folded to obtain packaging sleeves. On one face the mandrel has a recess which extends in the length dimension of the mandrel and in which a first pressing shoe is arranged for reciprocation parallel to the mandrel length. A face of the first pressing shoe complements a mandrel face to a continuous folder face. A second pressing shoe cooperates with the first pressing shoe in pressing and bonding together overlapping edge zones of the blank folded about the mandrel. The first and the second pressing shoes are—as they press the overlapping edge zones—movable as a unit together with the packaging sleeve relative to the mandrel parallel to its length dimension. In this manner the packaging sleeve is stripped from the mandrel, while the adhesive between the overlapping edge zones sets as the stripping takes place.

APPARATUS FOR MAKING PACKAGING SLEEVES

BACKGROUND OF THE INVENTION

This invention relates to an apparatus for making packaging sleeves from sheet blanks. Each blank is folded about a mandrel and the overlapping edge zones of the blank are pressed and bonded to one another and subsequently the obtained packaging sleeve is stripped from the mandrel. Such an arrangement, which provides a longitudinal seam on the packaging sleeves has been long known. After stripping the bonded sleeve from the mandrel, the sleeve is advanced to stations of 15 a packing machine.

According to a known arrangement of the above-outlined type, such as disclosed, for example, in U.S. Pat. No. 3,530,773, the operational phase including the stripping of the packaging sleeve from the mandrel is particularly circumstantial because the tools (such as pliers or the like) used for stripping can damage the sleeve which firmly surrounds the mandrel, since these tools engage only a relatively small portion of the sleeve and thus exert a large local force thereon. This difficulty is often increased by the fact that excess quantities of the adhesive may solidify on the mandrel and thus the adhesion of the sleeve to the mandrel is further increased.

A further disadvantage of known arrangements of the above-outlined type resides in their slow operation because of a waiting period between forming the sleeve and removing it from the mandrel to allow setting of the adhesive to ensure a satisfactory bond between the overlapping edge zones of the packaging sleeve.

SUMMARY OF THE INVENTION

It is an object of the invention to provide an improved apparatus of the above-outlined type from which the discussed disadvantages are eliminated.

This object and others to become apparent as the specification progresses, are accomplished by the invention, according to which, briefly stated, the mandrel has a recess extending along the length dimension of the mandrel and receiving a first pressing shoe which is longitudinally displaceable with respect to the mandrel and which complements the cross-sectional shape of the mandrel to a continuous folding face. A second pressing shoe cooperates with the first pressing shoe by urging overlapping edge zones of the packaging sleeve to one another. There is further provided a conveying device for moving the pressing shoes, while they grasp the packaging sleeve, away from the mandrel, thus stripping the sleeve from the mandrel. Thereafter the pressing shoe release the packaging sleeve and then return to the mandrel for a new cycle of operation.

The disadvantages discussed above are eliminated by the invention because the packaging sleeve is, during stripping, firmly held between the longitudinal pressing device (formed of the two pressing shoes) along the entire adhesive or sealing surface of the edge zones of the sleeve, whereby the danger of ruptures or the like is eliminated. Further, the stripping operation may start practically immediately subsequent to the compression 65 of the edge zones, because the setting of the adhesive or the like can be allowed to occur while the stripping operation is in progress.

BRIEF DESCRIPTION OF THE DRAWINGS

FIG. 1 is a schematic side elevational view of a preferred embodiment.

FIG. 2 is a sectional view taken along line II—II of FIG. 1.

FIG. 3 is an end elevational view of a component taken in the direction of the arrow III of FIG. 1.

FIG. 4 is a sectional view of a component shown in 10 FIG. 2, but depicted in a different operational phase.

FIG. 5 is a sectional elevational end view of a modification of the component shown in FIGS. 2, 3 and 4.

DESCRIPTION OF THE PREFERRED EMBODIMENTS

Turning now to FIGS. 1 and 2, the apparatus illustrated therein has a supply track 1 for feeding rectangular cardboard blanks 2. At the discharge end of the track 1 there are provided feed rolls 3 which advance the blanks 2 while they glide on two pairs of support rails 4 secured to the machine frame. An arm 6 pivotally supported on the machine frame at 5, pushes each blank 2 to a pair of abutments 7, where the blank 2 stops as illustrated at 2₁. The abutments 7 are mounted on two support brackets 8 which carry the respective shaft 9 of two pivotal arms 10 and 11 which, in turn, are provided at their free ends with folder wings 12 and 13. Between the two support brackets 8 there is arranged a vertically oriented guide sleeve 14 in which there is guided a vertically reciprocating tube 15 which, in turn, guides a ram 16 in its interior. On its upper end, the tube 15 carries a plate 17, from opposite edges of which there extend upwardly two vertical folder panels 18. The ram 16 is provided at its upper end with a head 19 which is supported on the plate 17 by means of a compression spring 20.

Upon upward movement of the tube 15, first the folder panels 18 and immediately thereupon, the head 19 engage the blank 2₁. The head 19 presses the blank in 40 an elastically yielding manner against the underside of an elongated, horizontally oriented stationary mandrel 21. At the same time, the folder panels 18 fold the blank 2₁ at opposite sides, in cooperation with the respective mandrel sides. The stroke of the folder panels 18 is 45 designated at h in FIG. 2. FIG. 4 illustrates how the head 19 holds the blank 2₂ against the underside of the mandrel 21. Subsequently, the arms 10 and 11 are pivoted upwardly and inwardly, thus folding the blank over the top face of the mandrel. A recess 22 of rectangular cross-sectional outline is provided in an upper corner zone of the mandrel 21, along the entire length thereof. A countershoe 23 is received in the recess 22 along its entire length. The countershoe 23 is movable independently from the mandrel 21 in the longitudinal direction and complements the profile of the mandrel 21 into continuous top and lateral folder surfaces. A longitudinal pressing shoe 24 subsequently presses the now overlapping edge zones of the blank 2₂ against the upper face of the countershoe 23 as it may be particularly well 50 observed in FIG. 2. One of the edge zones of the blank is provided with an adhesive or a sealing material such as glue or hot melt, so that the overlapping edge zones are firmly bonded to one another by the pressure exerted by the cooperating pressing shoes 23 and 24. In 55 this phase the blank is designated at 2₃ in FIG. 2.

The prismatic sleeve 2₃ has to be subsequently stripped from the mandrel 21. For this purpose the pressing shoes 23 and 24 which hold firmly the sleeve

²³, are shifted as a unit in the longitudinal direction relative to the mandrel ²¹ as it will be described below in greater detail. The pressing shoes ²³ and ²⁴ carry the sleeve ²³ with them as they are longitudinally shifted.

The horizontally oriented elongated mandrel ²¹ is secured at its left end (as viewed in FIG. 1) to a carrier ²⁵ which is fixedly secured to the machine frame. A support bracket ²⁶ which is mounted on the carrier ²⁵ and an only partially shown other support bracket ²⁷ hold a guide rod ²⁸ at its two ends. A carriage ²⁹ is slidably mounted on the guide rod ²⁸ which has a rectangular cross-sectional outline cooperating with a correspondingly shaped opening in the carriage thus preventing a pivotal motion of the carriage ²⁹ about the rod ²⁸.

There is further provided an L-shaped component ³⁰ which has a vertical leg ³¹, the upper end of which is secured to the carriage ²⁹. The other, horizontal leg of the L-shaped component ³⁰ constitutes the countershoe ²³ which extends in the recess ²² and which tapers slightly in the direction of its free end. The countershoe ²³ extends substantially parallel to the length dimension of the mandrel ²¹. This arrangement is advantageous, in that it makes possible a short structural length of the apparatus.

The carriage ²⁹ further carries a vertically oriented guide sleeve ³² in which there is slidably held a bar ³³. The inner cross-sectional outline of the sleeve ³² and the cross-sectional shape of the bar ³³ are such that the bar ³³ is prevented from turning with respect to the sleeve ³². The lower end of the bar ³³ is articulated to the longitudinal pressing member ²⁴ by means of a joint ³⁴. On the upper end of the bar ³³ there is mounted a head ³⁵ which is connected with the sleeve ³² by a powerful tension spring ³⁶ and which carries a roller ³⁷ arranged to travel on a horizontal rail ³⁸. The rail ³⁸ is secured at its ends to two arms ³⁹ (one shown in FIG. 2) which are pivotal as a unit by means of a shaft ⁴⁰. In FIG. 2, a lower position of the rail ³⁸ is shown in solid lines whereas an upper position of the same, together with the roller ³⁷ and the head ³⁵ is shown in phantom lines at ^{38'}, ^{37'} and ^{35'}, respectively. The rail ³⁸ is pivoted into the upper position ^{38'} in order to lift the longitudinal pressing member ²⁴ away from the mandrel ²¹ to thus discontinue its pressing effect, as it will be described below.

On the upper side of the carriage ²⁹ there are provided two eyelets ⁴¹ to which, at ⁴², there is articulated an actuating bar ⁴³ with the aid of which the carriage ²⁹ may be reciprocated on the guide rod ²⁸.

When the folding operation performed on a blank ² reaches approximately the phase shown in FIG. 4, the rail ³⁸ which is then in its upper position ^{38'} is pivoted downwardly (that is, the arms ³⁹ are swung clockwise as viewed in FIG. 2), whereupon the bar ³³ can be shifted by the spring ³⁶ in the downward direction, as a result of which the longitudinal pressing member ²⁴ presses the overlapping edge zones of the blank against the countershoe ²³. In response to this pressing force, the countershoe ²³ yields slightly; the longitudinal pressing member ²⁴ can, by virtue of the articulation ³⁴, readily follow the yielding motion of the countershoe ²³. In this position of the bar ³³, the roller ³⁷ is still at a small distance from the rail ²⁸ which is in its lower position, so that the rail ²⁸ does not obstruct the compression of the pressing shoes ²³ and ²⁴ to one another.

Subsequently, the carriage ²⁹ is displaced forwardly (that is, towards the right as viewed in FIG. 1) by means

of the rod ⁴³. Thus, as a result, the pressing shoes ²³, ²⁴ are likewise shifted, in their state pressed to one another, in the forward direction relative to the mandrel ²¹. The sleeve ²³ is thus carried by the pressing shoes ²³ and ²⁴ engaging it at its overlapping edge zones into the position ²⁴, thus stripping the sleeve from the mandrel ²¹. Since the sleeve ²³ is very firmly grasped by the shoes ²³, ²⁴ over a relatively large surface, there is no danger that the friction between the sleeve and the mandrel ²¹ cannot be overcome or that local ruptures in the blank will occur. As the carriage ²⁹ reaches its forward end position ^{29'}, the sleeve is displaced into a position ²⁴ in which it is accommodated in a U-shaped receiver ⁴⁴ (also shown in FIG. 3) which is mounted on a stand ⁴⁵.

Thereafter the rail ³⁸ is pivoted into its upper position ^{38'}, whereby the bar ³³ with the longitudinal pressing shoe ²⁴ is pulled upwardly against the force of the spring ³⁶ and thus the sleeve ²⁴ is released from the pressure of the pressing shoes ²³ and ²⁴.

Subsequently, as the carriage ²⁹ is pulled back towards the left into its earlier initial position, the roller ³⁷ rolls along the rail ^{38'} and thus maintains the bar ³³ in its upper position. After the pressing shoes ²³, ²⁴ release the packaging sleeve ²⁴, a grasping device ⁴⁶ is actuated for gripping a lateral wall of the packaging sleeve ²⁴ for pulling the same from the U-shaped receiver ⁴⁴ to thus advance the sleeve to additional, non-illustrated conveying arrangements. Since between the sleeve ²⁴ and the receiver ⁴⁴ no adhesion is present with the exception of the slight friction of the sleeve ²⁴ generated by its own weight, the tongue ⁴⁶ needs to exert only a slight force which in no way threatens damage to the sleeve ²⁴.

It is to be noted that the setting of the adhesive, which begins in the folded position ²³ of the blank, occurs preponderantly during the conveyance of the blank into its free position ²⁴; this circumstance results in a much more rapid operation of the apparatus than in prior art arrangements for making packaging sleeves.

The adhesive may be applied as early as during the making of the blank ² along one or both edge zones to be bonded to one another. It is, however, feasible to apply the adhesive by the above-described apparatus. For this purpose, on the carrier ²⁵ there is mounted an adhesive container ⁴⁷ which, at its lower portion, is provided with a dispensing nozzle ⁴⁸ by means of which an edge zone of the blank ² is, during its advance effected by the rollers ³, provided with an adhesive such as heated "hot melt". The adhesive cools (sets) during the described operation and effects a bond between the overlapping edge zones of the packaging sleeve.

It is further noted that the free end ²³² of the countershoe ²³ is situated in the same region of the overlapping edge zones of the blank ² as the free end ²¹² of the mandrel ²¹, as shown in FIGS. 1 and 4. Such an arrangement is advantageous, because if the vertical leg ³¹ of the L-shaped component ³⁰ is arranged in the zone of the free mandrel end ²¹², the path of the carriage ²⁹ would have to be made much larger in order to laterally push away the sleeve ²⁴ released by the pressure shoes ²³, ²⁴, to thus clear the way for the return motion of the pressing shoes ²³ and ²⁴.

It is further advantageous to provide the pressing shoe ²⁴ with an elastic element such as a rubber layer.

Turning now to FIG. 5, there is illustrated a variant ²¹¹ of the mandrel which in part corresponds to the

structure shown in FIG. 4. The recess 22₁ is, however, not provided along an upper mandrel edge as it was the case in the embodiment described before, but is arranged to extend longitudinally approximately in the middle of the upper surface of the mandrel 21₁. The groove-like recess 22₁ and the countershoe 23₁ shiftable therein have, as in the previously described embodiment, a rectangular cross section, whereby the longer side of the rectangle is oriented vertically in order to ensure a large resistance torque thus ensuring only slight bending deformation. The embodiment shown in FIG. 4 would in most cases be the preferred structure, since the middle of the upper side wall of the packaging sleeve is then not interrupted by the overlapping edge zones. A provision of offset overlap as results from the FIG. 4 structure is advantageous regarding the application of prints (texts or designs) on the sleeve.

The mandrel and the countershoe extending in the recess of the mandrel need not necessarily complement each other to a rectangular profile. Such a profile in principle may be of any polygonal shape or maybe even of rounded configuration. It is to be understood that the blanks advanced into the apparatus may be provided with score lines and slots so that a bottom and a lid may be readily obtained by folding the end flaps of the sleeve

24.

FIGS. 1 and 2 further schematically show the drives of shafts 9 and 40, the ram 15 and the actuating rod 43 as well as the synchronization between these drives. Each drive comprises a respective cam disc 50_a, 51_a, 52_a, and 54. The cam discs 50_a to 53_a are provided at their radial faces with a respective cam track which, by means of follower rollers, displace respective levers 50_b, 51_b, 52_b and 53_b. The latter move the respective shafts 9 and 40 as well as the actuating rod 43. The drive of ram 15 includes the cam disc 54, the camming periphery of which cooperates with a slide plate 55, fixedly mounted on the ram 15. Thus, the cam disc 54 causes the plate 55 to follow its circumference thereby lifting ram 15 which is lowered due to his own weight or if necessary, by means of a spring (not shown).

The synchronization between the different drives is obtained by a common driving shaft 56 shown in broken lines for all cam discs 50_a to 53_a and 54. It is noted that, particularly in FIG. 2, the shaft 56 is shown to be multidirectional solely for purposes of the schematic illustration from which conventional push rods, linkages, plungers and similar driving elements are omitted for the sake of simplicity.

It is to be understood that the above description of the present invention is susceptible to various modifications, changes and adaptations and the same are intended to be comprehended within the meaning and range of equivalents of the appended claims.

55
What is claimed is:

1. In an apparatus for making a packaging sleeve from a sheet blank, including a mandrel having a length dimension; folder means for wrapping the sheet blank about the mandrel, whereby opposite free longitudinal edge zones of the blank are brought into an overlapping relationship on the mandrel; pressing means for pressing and bonding the overlapping edge zones to one another for obtaining a seam along the length dimension of the packaging sleeve; the improvement wherein said mandrel has a recess extending in said length dimension; said pressing means comprises an elongated first pressing shoe arranged to be receivable in said recess and to be displaceable in its length dimension parallel to the

length dimension of said mandrel; said first pressing shoe having at least one face that complements a face of said mandrel into a substantially continuous folder face; said pressing means further including a second pressing shoe arranged to cooperate with said first pressing shoe for pressing overlapping edge zones of the blank sheet to one another; said pressing means further comprising shoe moving means connected to said first and second pressing shoes for displacing said second pressing shoe 10 towards or away from said first pressing shoe into a pressing state and a released state, respectively, and for shifting said first and second pressing shoes as a unit relative to said mandrel and parallel to the length dimension thereof for stripping the packaging sleeve from said mandrel with said first and second pressing shoes.

2. An apparatus as defined in claim 1, wherein said mandrel has a rectangular cross-sectional outline when viewed together with the cross-sectional outline of said recess; said recess extending in a corner zone of said mandrel.

3. An apparatus as defined in claim 1, wherein said mandrel has a rectangular cross-sectional outline when viewed together with the cross-sectional outline of said recess; said recess extending in a face of said mandrel spaced from corner zones thereof.

4. An apparatus as defined in claim 1, wherein said mandrel is stationarily supported in said apparatus and having a free end; further wherein said shoe moving means comprises a carriage arranged spaced from said mandrel and displaceable parallel to the length dimension of said mandrel; further comprising an angled member having a first leg constituting said first pressing shoe; said first pressing shoe having a free end and being at least approximately parallel to the length dimension of said mandrel; said angled member having a second leg attached to said carriage such that said free ends of said mandrel and said first pressing shoe are situated in the same region of the overlapping edge zones of the blank sheet.

5. An apparatus as defined in claim 4, wherein said first pressing shoe tapers towards its free end and further wherein said first pressing shoe has a rectangular cross-sectional shape of short and long sides; one of said short sides forms a work face cooperating with said second pressing shoe.

6. An apparatus as defined in claim 1, wherein said shoe moving means comprises

- (a) a first guide rail extending spaced from said mandrel and parallel to the length dimension thereof;
- (b) a carriage mounted on said first guide rail for displacement therealong; said first pressing shoe being attached to said carriage;
- (c) a shoe holding member attached to said second pressing shoe;
- (d) mounting means attached to said carriage and coupling said shoe holding member to said carriage; said mounting means providing for a displaceability of said shoe holding member and said second pressing shoe towards and away from said first pressing shoe;
- (e) means for urging said second pressing shoe into said pressed state;
- (f) a movably supported second guide rail extending parallel to and spaced from said first guide rail and being operatively connected with said shoe holding member; said second guide rail having a first position in which it maintains said second pressing shoe in said released state and a second position in

- which said second pressing shoe is maintained in said pressed state;
- (g) first force-exerting means for shifting said carriage along said first guide rail; and
- (h) second force-exerting means for moving said second guide rail into its said first and second positions.
7. An apparatus as defined in claim 6, further comprising a roller mounted on said shoe holding member and arranged for a rolling engagement with said second guide rail for establishing an operative connection between said shoe holding member and said second guide rail.
8. An apparatus as defined in claim 6, wherein said mandrel is stationarily supported in said apparatus.

5

10

15

9. An apparatus as defined in claim 6, wherein said second pressing shoe is articulated to said shoe holding member.
10. An apparatus as defined in claim 6, wherein said shoe holding member comprises a holding bar.
11. An apparatus as defined in claim 10, wherein said mounting means comprises a sleeve through which said bar slidably passes.
12. An apparatus as defined in claim 6, wherein said means for urging said second pressing shoe into said pressed state comprises a spring.
13. An apparatus as defined in claim 12, wherein said spring is attached to said shoe holding member and said mounting means.
